(57) **CLAIM**

The ornamental design for a candlestick, as shown and described.

DESCRIPTION

FIG. 1 is a top perspective view of the candlestick according to my design;

FIG. 2 is a bottom perspective view thereof;

FIG. 3 is a front view thereof;

FIG. 4 is a rear view thereof;

FIG. 5 is a right side view, the left side view being a mirror image thereto;

FIG. 6 is a top plan view thereof; and,

FIG. 7 is a bottom view thereof.

The broken lines in the drawings showing the candlestick illustrate the portions of the candlestick that form no part of the claimed design.
